LIGHTING UNIT

Alphonse F. Pieper, Brighton, N. Y.

Application July 14, 1939, Serial No. 284,531

7 Claims. (Cl. 240—1.4)

My invention relates to a novel lighting unit particularly adapted for a dental office.

An object of my invention is to provide a lighting unit particularly suited for a dental office which may be manufactured at a reasonable cost and which furnishes, in a single lighting unit, the proper illumination desired for the dental office as a whole; the more intense illumination required for the field or area of the room in which 10 the instruments and apparatus which the dentist frequently uses are located; and the concentrated and intense illumination demanded for performing operations in the oral cavity.

My invention further contemplates a unitary 15 lighting fixture or unit for a dental office which furnishes, in a single unit, the proper intensity of light for each portion of the office without causing annoyance to the patient or dentist, while operations are being performed in the patient's 20 mouth.

Other objects and advantages of my invention will be particularly set forth in the claims and will appear from the following description, when taken in connection with the accompanying 25 drawings, in which:

Fig. 1 is a side elevation of my novel lighting unit;

Fig. 2 is an end elevation of the same;

Fig. 3 is a top plan view of the unit;

Fig. 4 is a sectional view taken through the unit;

Fig. 5 is a view taken on the line 5—5 of Fig. 4 in the direction indicated by the arrows; and

Fig. 6 is a view showing a slightly modified 35 form of my invention.

As shown in Fig. 1, the lighting unit, indicated generally by the numeral 11, is supported by means of a bale 12 from any suitable supporting means 13. When used in a dental office, for 40 which the unit is more particularly adapted, the support 13 is preferably carried by and constitutes part of the dental unit. The bale is pivotally secured, as indicated at 14, to the opposite sides of the unit.

As shown in Fig. 3, the lighting unit is preferably rectangular in shape and of sufficient size to contain the proper number and size of light elements required for proper illumination. As shown in Figs. 1—3, inclusive, each side of the unit 50 is provided with a side plate 16 which may be of metal or a plastic product to which the bosses 17 for pivotally receiving the bale are secured. Secured also to each side plate 16 is a hand rod 18. The hand rods 18 extend completely across the 55 sides of the unit and may be conveniently

grasped when the dentist is at any position adjacent the lamp so that he may tip the lamp to concentrate the light as desired.

As shown more clearly in Figs. 4 and 5, a pair of preferably arcuate end shields 19 are supported from the side plates 16, and have lips 21 for supporting a bottom plate of glass 22. The plate of glass 22 is suitably sanded, rippled, or otherwise treated to transmit and diffuse the light without glare. In the upper sides of the 10 frame, and suitably supported from the side plates, are a pair of glass plates 23 which are also suitably treated to transmit and diffuse the light without glare. Preferably, the plates extend at an angle to the plates 22, as shown in the drawings.

Arranged in the lighting unit are a plurality of light sources, which are generally indicated by the numerals 24 and 26. Preferably, the light sources are of the fluorescent electric discharge 20 type employing mercury vapor as the medium for sustaining the arc. Further, the light sources have daylight color correction. Light sources of this character are well known in the art of lighting and need not be more particularly described. As shown in Fig. 3, the light sources are in the form of tubes which extend from one side of the unit to the other. Preferably, the character of the light sources chosen is such as to require low energy.

The light sources 24 are provided with reflectors 27 which may be parabolic in shape although the exact shape of the reflectors is not important. Brackets 30 secured to the side plates and interfitting with the reflectors, as shown at 30' (Fig. 35 5), are provided to support the reflectors. The reflectors 27 are arranged to throw the light, with the position of the parts shown in the drawings, downward and to provide an intense and concentrated, although diffused, illumination for enabling the dentist to operate in the oral cavity. By the use of three light sources spaced relatively close together and with adequate reflectors, the light may be directed on and in the patient's 40 mouth and all operations performed without any additional light except those requiring visibility at the extreme rear of the oral cavity. Where operations at the extreme rear of the oral cavity are to be performed, in some cases, the dentist needs in addition a small hand-controlled 45 light adapted to be projected into the patient's mouth and concentrated on the portion to be operated upon. The light sources 26 are provided with suitable reflectors 28 supported by brackets carried by the side plates so as to di- 50 55

rect the light, with the position of the parts shown in the drawings, in an upward direction. Preferably also, these reflectors are parabolic in shape, although other shapes of reflectors may be used if desired.

Supported between the side plates is a shelf or trough 29 which is adapted to support the reactors forming a part of the electric circuit of the light tubes, as is well understood in the art of lighting. Since the lamp in its preferred form employs five light sources, five reactors are required which may be supported adjacent each other on the shelf 29. At the top of the unit and extending between the side plates is a top shield 31 which serves to cover the reactors and extends slightly over the edges of the glass plates 23, as shown at 32.

The unit is mounted so that it is at the proper elevation to enable the dentist to reach conveniently the hand rods 18 of the unit for adjusting its angular position with respect to the horizontal so as to direct the rays from the light sources 24 onto the patient. The direct light emanating from these three closely spaced sources, aided by reflectors, is concentrated and intense, although diffused by reason of the character of the sources of light used and the use of the diffusing plate 22. This direct illumination is of such intensity that the dentist can perform most operations in the oral cavity without requiring any further illumination. In certain cases when the extreme rear of the oral cavity must be operated upon, a small lamp, the light of which is projected into the mouth, may be necessary.

The light sources 26 are directed toward the ceiling and sides of the room and provide indirect illumination. The indirect light is reflected from the walls into a field or area closely adjacent the unit so as to properly illuminate the unit, particularly the tray upon which the instruments are supported and the adjacent apparatus which the dentist frequently uses. Considerable illumination is required for this purpose, as the dentist must take from the tray objects so small that tweezers are required. Moreover, the dentist requires a light closely adjacent his unit of sufficient intensity to enable him to match the various shades of teeth and porcelain, and the reflected light from the sources 26 is sufficient for this purpose. At the same time the remainder of the room is lighted sufficiently by indirect light to permit ordinary operations to be carried on in the remainder of the room, such as when the dentist goes to his cabinet to select materials or additional instruments.

Of particular advantage in connection with my light unit is the fact that the sources of indirect light are hidden behind and blocked out by the sources of direct light so that neither the patient nor the dentist is conscious of any other light source in the room which is annoying to some people, particularly when an operation is being performed. Regardless of the position of adjustment of the unit so as to direct the rays properly for purposes of operating on the patient, the source of indirect light moves therewith so as to be always hidden from the patient and from the dentist.

In Fig. 6 I have shown a slightly modified form of my invention in which the general arrangement is substantially the same as that described above. However, in this instance the reflectors are separated from each other so that a space 36 exists between adjacent reflectors 27. Cooperating with these spaces, in each of the reflectors

28 there is provided a longitudinally extending slot 37 through which a portion of the light from the sources 26 is directed so that the light sources 26 tend to aid the light sources 24 in providing a greater intensity of direct illumination. Similarly, the reflectors 27 are provided with longitudinally extending slots 38 through which a portion of the light from the light sources 24 is directed upward to increase the intensity of indirect illumination. The advantages of this form 10 of my invention are the same as in the previous form.

While I have described the preferred forms of my invention, it will be apparent that various changes and modifications may be made therein, particularly in the form and relation of parts, without departing from the spirit of my invention as set forth in the appended claims.

I claim:

1. A lighting unit comprising a single unitary 20 frame, a set of straight line light sources mounted therein for one character of illumination, reflecting means for said sources, a set of light sources for a second character of illumination located on the opposite side of the unit, reflecting means 25 for said sources, said reflecting means lying between the two sets of sources, one of said reflecting means having slots through which a part of the rays of light from the associated sources may pass and intensify the illumination from the 30 other light sources.

2. A lighting unit comprising a single unitary frame, a set of straight line substantially parallel fluorescent light sources mounted substantially in one plane, a second set of substantially parallel fluorescent light sources mounted substantially in a plane above the plane of said first set, an individual concave trough shaped reflector for each of said light sources, the reflectors for the two sets of light sources being 40 staggered and arranged in back to back substantially contiguous relation to each other whereby the overall height of the unit is maintained at substantially a minimum, and a plurality of reactors for said light sources carried by said frame 45 and nested between two of the reflectors of one of the sets of light sources.

3. A lighting unit comprising a single unitary frame, a set of straight line parallel fluorescent light sources mounted in said frame, a second 50 set of straight line substantially parallel fluorescent light sources mounted in said frame above said first set, an individual concave trough shaped reflector for each of said light sources, the reflectors for the two sets of light sources 55 being arranged in back to back substantially contiguous relation to each other whereby the overall height of the unit is maintained at substantially a minimum, and a plurality of reactors for said light sources carried by said frame and 60 nested between two of the upper reflectors so that the light from either reflector will not be intercepted by said reactors.

4. A lighting unit for a dental office to give 65 indirect general room illumination and concentrated illumination for enabling the dentist to operate within the oral cavity, said unit comprising a frame, a plurality of straight line parallel fluorescent light sources mounted in said frame, a separate concave trough shaped reflector for 70 each of said light sources mounted in said frame so as to concentrate the light from said light sources in an intense field of illumination upon the patient and upon the dentist's work space adjacent the patient, a second set of straight line 75

parallel fluorescent light sources superposed in said frame with respect to said first set, a separate concave trough shaped reflector for each of said second set of light sources mounted in said frame in back to back substantially contiguous relation with said first set, said second set having its reflectors arranged angularly to each other to direct the rays of light divergently upward for general room illumination, and reactors mounted 5 in said frame between some of said reflectors.

5. A lighting unit for a dental office to give general indirect room illumination and concentrated illumination for enabling the dentist to operate within the oral cavity, said unit comprising a 15 frame, a plurality of straight line parallel fluorescent light sources mounted in said frame, a separate concave trough shaped reflector for each of said light sources mounted in said frame so as to concentrate the light from said light sources in 20 an intense field of illumination upon the patient and upon the dentist's work space adjacent the patient, a second set of straight line parallel fluorescent light sources superposed in said frame with respect to said first set, a separate concave 25 trough shaped reflector for each of said second set of light sources mounted in said frame in

back to back substantially contiguous relation with said first set to maintain the overall height of the unit at a minimum, and arranged to give general indirect room illumination, and reactors mounted in said frame, a support and a bail connected to said support and pivotally attached to the frame and extending above and across the same between the upper reflectors to enable the frame to be swung so as to concentrate the light 10 for operating within the oral cavity as desired with the source of general indirect room illumination being hidden from the patient's view and with the light from said upper reflectors being substantially unobstructed by said bail.

6. A lighting unit as set forth in claim 3 and 15 wherein there are provided diaphanous sheets of material for diffusing the light from said light sources and together with the frame completely enclosing the light sources.

7. A lighting unit as set forth in claim 5 and 20 wherein are provided diaphanous sheets of material arranged angularly to each other for diffusing the light from said light sources and together with the frame completely enclosing the light 25 sources.

ALPHONSE F. PIEPER.
